C. J. DUNBAR

LOOSE LEAF BINDER

Filed June 9, 1919

UNITED STATES PATENT OFFICE.

CHARLES J. DUNBAR, OF KALAMAZOO, MICHIGAN, ASSIGNOR TO THE WILLIAM C. WINDISCH COMPANY, OF DETROIT, MICHIGAN, A CORPORATION OF MICHIGAN.

LOOSE-LEAF BINDER.

Application filed June 9, 1919. Serial No. 302,731.

To all whom it may concern:

Be it known that I, CHARLES J. DUNBAR, a citizen of the United States of America, residing at Kalamazoo, in the county of 5 Kalamazoo and State of Michigan, have invented certain new and useful Improvements in Loose-Leaf Binders, of which the following is a specification, reference being had therein to the accompanying drawings.

10 The invention relates to leaf binders of that type in which the apertured leaves are engaged with posts on one cover section of the binder and are clamped by a second cover section engageable with said posts and 15 locked thereto. More particularly, the invention relates to constructions in which the locking of the clamping section with the posts is effected through the medium of a ball clutch. With such constructions the 20 clamp is released by a lever or other actuating means which directly engages the ball and removes the same from locking position and heretofore such releasing mechanism has been actuated by means protruding from 25 the side of the cover. It is one of the objects of the present invention to avoid any protruding parts and to control the lock by means included within the external dimensions of the binder. It is a further object 30 to obtain a simple easily operated mechanism as hereinafter set forth.

In the drawings:

Figure 1 is a section through a binder to which my improvements are applied; 35 Figure 2 is a perspective view of the locking and releasing mechanism removed from the binder cover;

Figure 3 is a sectional plan view showing the locking and releasing mechanism slightly 40 modified from Figure 2;

Figure 4 is a similar view showing another modification;

Figure 5 is a section on line 5—5 of Figure 4; and

45 Figure 6 is a section similar to a portion of Figure 1, showing another modification.

A is the section of the cover to which the posts B are attached, and C is the removable cover. The posts B may, if desired, be 50 formed of a series of sections B, B', B'', etc., having threaded or other coupling engagement with each other, so that the length may be varied according to the number of leaves to be bound. D are blocks detachably secured within a hollow casing mem-

ber E which forms a portion of the cover section C, said blocks being apertured at F for engagement with the posts B. G are recesses in the block at one side of the aperture F having inclined faces G', and H are 60 balls in said recesses forming friction clutches between the inclined faces G' and the posts B. I is a releasing device for the ball in the form of a flat lever engaging a slot in the block D and fulcrumed upon 65 the pin J. The free end I' of this lever projects into the recess G and is bifurcated to embrace the ball H, as shown in Figure 5.

The construction as thus far described has 70 heretofore been used, but for actuating the lever I it has been customary to provide a member protruding from the side of the cover. This is objectionable as it interferes 75 with the stacking of the binders and resting of the same upon the removable cover. I have therefore provided an actuating device which is completely included within the dimensions of the binder and which may be 80 operated from one edge of the cover. 80

As shown in Figure 2, K is a rod passing through groove L in the block D on the side thereof farthest removed from the ball H. M is a handle at the outer end of the rod K for actuating the same, and N are 85 arms projecting from said rod into operative engagement with the levers I. As specifically shown in Figure 2, the handle M forms a crank arm for rocking the rod K and the arms N pass through slightly enlarged apertures O in the levers I so that when the rod K is rocked in one direction, the lever will be actuated to release the ball and when rocked in the opposite direction will return the ball to locking position. The handle M, as shown in Figure 3, is 90 arranged within the end portion of the hollow casing E, but said casing is cut away, as indicated at P, so that the operator has access to the handle for rocking the same. In this figure, the arm N instead of passing through an aperture in the lever I², merely 95 engages one edge of said lever for operating the same to released position while a spring located in an aperture Q in the block D will return the lever to locking position. The arrangement of the spring and lever is more specifically shown in Figure 5, but the actuating device for the lever is modified to 100 operate by a longitudinal movement of the 105 110

rod K. The rod K' may be moved longitudinally from the positions shown respectively in full and dotted lines and during this longitudinal movement, the arm N' co-operating with a cam face R on the lever I³ will rock said lever to release the ball. With the last described modification means must be provided for limiting the longitudinal movement of the rod K which as shown consists in collars T and T' thereon on opposite sides of a bearing block U within the hollow casing. There is also provided a resilient latching device comprising the spring V which in one position engages a notch in the rod K' but from which it may disengage by a slight force exerted on the handle M'. With the construction shown in Figure 2, the rod K is held from longitudinal movement by having a threaded engagement W with a block W' arranged within the hollow casing E.

With all of the various modifications described, the general operation is the same and is as follows: The cover C is engaged with the ends of the posts and is then pressed inward against the leaves. With the construction in Figure 2, the handle M is then rocked and through the medium of the rod K and rock arms N will actuate the levers I so as to force the balls H into locking engagement with the posts. With the constructions shown in Figures 3 and 5, the locking will be automatically effected by the operations of the springs Q'. Whenever it is desired to release the clamp, the handle M is actuated in the opposite direction, which by oppositely rocking the levers I will force the ball H out of locking engagement, whereupon the cover C is released.

With the constructions shown in Figures 4 and 5, the only difference in operation is the movement of the handle M' longitudinally instead of rocking it, this effecting a corresponding rocking movement of the lever I³.

In the construction shown in Figure 6, instead of having the posts B of cylindrical form with parallel sides, the upper section of said posts is grooved and flares towards the upper end thereof. The angle of this flare is less than the angle of the inclined face G² in the recess containing the ball, so that the ball may be released from locking position by a movement of the lever I in the same manner as previously described.

One important feature of my improvement is that the clutch when adjusted to releasing position remains released and when adjusted to engaging position, will automatically engage. This is effected in the constructions shown in Figures 2 and 3 by the friction between the rod K and its bearings, which is sufficient to hold the same from accidental turning. With the

construction shown in Figure 4, the friction on the rod of the resilient latch V is sufficient to hold it from movement. Thus, when the operator wishes to remove the cover, by first operating the handle to releasing position of the clutch, he may then throw off the cover without continuing pressure on the operating handle.

While a ball clutch is shown and specifically described, it is obvious that some other form of clutch may be used in place thereof.

What I claim as my invention is:

1. In a binder, the combination of a post, a cover section having an apertured block engageable with said post, a ball in a recess in said block having a clutching engagement with said post, a lever pivoted in said block and engageable with said ball to move the same from locking to releasing position, a rod extending within said cover section having an actuating handle adjacent to one edge of said cover section for moving the same, and means intermediate said rod and lever for actuating the latter from the former.

2. In a binder, the combination of a post, a cover section having an apertured block for engaging said post, a ball in a recess in said block having clutching engagement with said post, a lever pivoted in said block engaging said ball to move the same from locking to releasing position, a rod extending within said cover section, a handle adjacent to one edge of said cover section movable to rock said rod, and a rock arm projecting from said rod into engagement with said lever, whereby the rocking of the rod will effect a movement of the lever to release the clutch.

3. In a binder, the combination of a post, a cover section having a block engageable with said post, a ball in a recess in said block having a clutching engagement with said post, said post being provided with a flaring section for engagement with said ball, and said block having an inclined face engaging the ball and at an angle to the flaring face of said post.

4. In a binder, the combination of a post, a cover section having an apertured block engageable with said post, means in a recess in said block having a clutch engagement with said post, a lever pivotally mounted on said block and engageable with said means to move the same from locking to releasing position, a rod extending within said cover section having an actuating handle adjacent to one edge of said cover section for moving the same, and means intermediate said rod and lever for actuating the latter from the former.

In testimony whereof I affix my signature.

CHARLES J. DUNBAR
